CLAIM

The ornamental design for a professional pilot master log, as shown and described.

DESCRIPTION

FIG. 1 is master document locator panel one of the professional pilot master log, shown separately for ease of illustration;

FIG. 2 is the left side of panel two of the professional pilot master log, shown separately for ease of illustration;

FIG. 3 is the right side of panel two of the professional pilot master log, shown separately for ease of illustration;

FIG. 4 is panel three of the professional pilot master log, shown separately for ease of illustration;

FIG. 5 is panel four of the professional pilot master log, shown separately for ease of illustration;

FIG. 6 is the left side of panel five of the professional pilot master log, shown separately for ease of illustration; and,

FIG. 7 is the right side of panel five of the professional pilot master log, shown separately for ease of illustration.

The broken lines in each view represent the bounds of a portion of the professional pilot master log and form no part of the claimed design.

The “Aircraft Cockpit and Globe” logo trademark/service mark forming part of the claimed design are registered trademark/service marks belonging to Dr. Eric Kudimi.
